(57) **CLAIM**

The ornamental design for a pet collar, as shown and described.

DESCRIPTION

FIG. 1 is a front, left and bottom perspective view of a pet collar showing my new design;

FIG. 2 is a rear, right and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view of the pet collar in a unfolded state.

The broken lines are representing stitching of the pet collar and the broken lines form no part of the claimed design.

1 Claim, 9 Drawing Sheets
